UNITED STATES PATENT OFFICE.

LOUIS BARCELOUX, OF ST. HYACINTHE, QUEBEC, CANADA.

SKIRT-FITTING DEVICE.

1,318,474.

Specification of Letters Patent.

Patented Oct. 14, 1919.

Application filed May 3, 1919. Serial No. 294,497.

To all whom it may concern:

Be it known that I, LOUIS BARCELOUX, a subject of the King of Great Britain, residing at St. Hyacinthe, Province of Quebec, 5 Canada, have invented certain new and useful Improvements in Skirt-Fitting Devices; and I do hereby declare that the following is a full, clear, and exact description of the invention, such as will enable others skilled in 10 the art to which it appertains to make and use the same.

The invention relates to improvements in devices for fitting skirts and the principal object resides in the provision of means for 15 accurately determining the proper length and width of the garment during the fitting operation.

A further object of the invention is to provide a gaging device which is adjustable 20 in horizontal and vertical planes, so that the proper width and length of the skirt can be quickly ascertained and same may be altered at a single fitting.

A further object of the invention is to provide serrations on one of the members for 25 the insertion of the stitches at the bottom of the skirt.

A still further object of the invention is to provide a device, wherein the ring member 30 is adjustable in a diametrical plane.

With the above and other objects in view which will hereinafter appear as the description continues, the invention consists of the 35 novel features of construction, combination and formation of parts as will be hereinafter more fully described and particularly pointed out in the appended claim.

In the accompanying drawings has been shown a simple and preferred form of the 40 invention, it being, however, understood that no limitation is necessarily made to the precise structural details herein exhibited, but the right is hereby reserved to any changes, alterations or modifications to which re- 45 course may be had that come within the scope of the claim without departing from the spirit of the invention or sacrificing the efficiency of the same.

In the accompanying drawings: 50 Figure 1 is a perspective view of my improved fitting device and the supporting stool thereof;

Fig. 2 is a fragmental side elevation illustrating the application of the device to a 55 skirt;

Fig. 3 is an enlarged detail elevational

view of the adjustable ring member with portions broken away;

Fig. 4 is an enlarged sectional view of the vertical adjusting elements; 60

Fig. 5 is a modification of the ring member; and,

Fig. 6 is a sectional elevation of the ring.

Referring now more particularly to the accompanying drawings wherein like and 65 corresponding parts are designated by similar reference characters throughout the several views.

In the device illustrated in the drawings, the numeral 1, denotes a low settee member, 70 comprising a platform 2, supported on legs 3, the latter being connected by the usual rounds 4.

The lower surface 5 of the platform 2, adjacent one end has secured thereto, a collar 6, 75 having an aperture and said aperture is in register with a similar opening in the platform.

A vertical post 7 is adjustably mounted in the openings in the collar 6 and platform 2 80 respectively, and carries at its upper end the cross bars 8. A split ring 9 is secured in any desirable manner to the cross bars 8 and serves as the supporting means for the same. 85

The collar 6 is likewise provided with a transverse opening adapted for the reception of a wing bolt 10, the inner shank 11 of which engages the lower end of the vertical post 7, to hold the same in adjusted position 90 on the settee.

The ring 9 is adjustable to vary the diameter thereof, by means of a band 12, which latter is secured by rivets 13 to one of the free ends of the rings, while the opposite 95 end of the band 12 is slotted at 14 and a bolt 15 is mounted in the opposite free end of the ring and carries a wing nut 16.

The ring 9 on its lower marginal edge is formed with a plurality of spaced serrations 100 17, which latter, when the ring is positioned as illustrated in Fig. 6, afford the entrance of a needle for stitching the inturned or seam portion at this point, the cloth being folded over to position the lower edge of 105 said ring in the crease. In this manner the proper draping of the skirt is assured and the lower edge of same will hang uniformly with the platform.

In the modification illustrated in Fig. 5, 110 the ends of the ring member 9 overlap and the said ends are formed with registering

slots 18 and a bolt 19 passes through said slots and carries a wing nut 20. By adjusting this ring member 9 the relative diameter is altered.

- 5 When a skirt is to be fitted as illustrated in Fig. 2, the party steps upon the settee within the ring 9, which latter has been lowered, then the ring is adjusted on the post 7, by the adjustment of the wing bolt 10, to the height desired, which will represent the length of the skirt. Then the ring 9 is adjusted, by bringing together or spacing apart the free ends thereof and thus the width of the skirt is obtained.
- 10 15 It will thus be seen that these measurements may be accurately and speedily made, and in use as illustrated in Fig. 6, the ring 9 is positioned above the skirt line and the material is turned in at the bottom and basted, by passing the needle and thread through the serrations or openings 17 and when such basting is completed, the skirt may be then taken off and completed.

Copies of this patent may be obtained for five cents each, by addressing the "Commissioner of Patents; Washington, D. C."

Having thus fully described my invention, what I claim as new and desire to secure by Letters Patent is:

A skirt fitting device comprising a settee member for supporting the person to be fitted, a collar carried by the settee member, a vertical bar adjustably mounted in said collar, a bolt for holding said post in adjusted position within said collar, a split ring carried by said post, a band connected to one end of said ring, the other end of said band being slotted, a bolt arranged in the other end of said ring and disposed within the slotted portion of said band and a nut carried by said bolt and adapted to hold said ring in adjusted position.

In witness whereof I have hereunto set my hand.

LOUIS BARCELOUX.
